(57) **CLAIM**

The ornamental design for a protector for a sprinkler head,
as shown and described.

DESCRIPTION

FIG. 1 is a front elevational view of a protector for a
sprinkler head showing my new design;

FIG. 2 is a rear elevational view thereof;

FIG. 3 is a right side elevational view thereof; a left side
elevational view thereof being a same image;

FIG. 4 is a top plan view thereof;

FIG. 5 is a bottom plan view thereof;

FIG. 6 is a cross-sectional view thereof taken along line 6-6
in FIG. 1;

FIG. 7 is a perspective view thereof of the front, top and
right side; and,

FIG. 8 is a perspective view thereof, of the front, bottom and
right side.

1 Claim, 8 Drawing Sheets
